UNITED STATES PATENT OFFICE

LORENZO SANSONE AND CESARE FRANCO, OF NEW YORK, N. Y.

PERCUSSION INSTRUMENT

Application filed June 12, 1931. Serial No. 543,785.

This invention relates to musical instruments of the "percussion" group and more particularly to a percussion instrument which combines the qualities of a tympano and snare drum.

Two or three of the conventional tympani are considered an essential part of any well balanced concert or symphony orchestra. Likewise, a snare drum is equally necessary and its use is frequently required. The space for the orchestra in the pit or on the stage is almost invariably limited and the percussion instruments require more space than a great many other instruments.

It is one of the principal objects of the present invention to provide a conventional tympano which, by a rapid manipulation of levers, may be converted into a snare drum, thereby enabling the space otherwise required for the snare drum to be utilized for other purposes, and eliminating the necessity for transporting a snare drum when the orchestra is in transit.

Another object of the invention is the provision of a novel percussion instrument which is capable of producing all of the beautiful effects of the tympano or tuned drum, and which may be converted into a percussion instrument capable of producing the brilliant, staccato effect of a snare drum, the change from one to the other being instantaneous and effective.

Still another object of the invention is the provision of simple means for attachment to a conventional tympano whereby this snare drum effect may be secured.

Other objects and advantages of the invention will be hereinafter specifically pointed out, or will become apparent, as the specification proceeds.

With the above indicated objects in view, the invention resides in certain novel constructions and combinations and arrangements of parts, clearly described in the following specification and fully illustrated in the accompanying drawings, which latter show embodiments of the invention as at present preferred.

In said drawings:

Fig. 1 is a partial top plan view of a con-

ventional tympano and showing, in broken lines, the embodiment mounted therein.

Fig. 2 is a vertical section taken substantially through the center of a tympano and showing a side elevation of the embodiment.

Fig. 3 is a plan view of the damper means.

Fig. 4 is a side elevation of same.

Fig. 5 is a perspective view of one end of the damper means and illustrating the preferred method of securing the strings.

Fig. 6 is a perspective view of the opposite end of the damper means and showing the adjusting or tuning means for the strings.

Fig. 7 is a perspective view of the sliding string carrier.

Fig. 8 is a perspective view of the foot pedal for actuating the device.

Referring now to said drawings by reference characters, the embodiment, as at present preferred, includes a damper member 10 and means for moving same into engagement with the under side of the head 11 of a conventional tympano or kettledrum 12.

The usual tympani includes a relatively large semi-spherical metal body structure 13 which is mounted on a suitable stand or pedestal 14. The head 11 is made from a suitable skin which is secured taut over a metal hoop, the hoop being drawn downwards over the upper edge of the body structure by means of a plurality of adjustable clamping members 15, this adjusting being required to produce the correct "pitch" or musical note when the instrument is played. When the damper member, constructed in the manner herein-after described, is moved into engagement with the lower surface of the head 11 and the head struck with snare drum sticks in that portion of the head engaged by the damper the resulting effect is precisely the same as that obtained on a snare drum.

The damper may be constructed in a variety of ways. We prefer to employ a base member 16 constructed of wood, metal, or other suitable material, one end of which carries a rectangular clamp 17, on the top of which is mounted a U shaped channel member 18 which carries a piece of felt or other resilient material 19, the latter forming a bridge over which a plurality of

strings 20 are suspended in spaced relation to the base member 16.

The clamp 17 also carries a U shaped block member 21 which extends over the end portion 22 of the base member. The strings are secured, at this end of the base member, between the end portion 21 of the block member 21 and a bar 23 which may be tightly drawn to the end portion 21 by means of a plurality 10 of screws 24.

In order to provide means for adjusting the strings to the desired pitch the opposite ends of the strings are secured to a sliding string carrier 25, shown in detail in Fig. 7.

- 15 This carrier includes side portions 26, an upper portion 27, a lower portion 28 having a cut away part 28'; and an upturned string engaging portion 29, integral with the upper portion 27, and having a plurality of staggered string apertures 30. A U shaped channel member 31 is mounted on the upper portion 27 of the string carrier, just ahead of the string engaging portion, said channel member carrying a piece of felt 32 which 20 likewise functions as a bridge for this end of the damper.

The following means are provided for adjusting the string carrier. A U shaped bracket 33 is secured, at its base 33, to the 30 under side of the member 16. The vertical side portions 34 and 35 are provided with apertures 34' and 35' in which are carried a screw 36 which is provided with threads 37 at its outer end, a wing nut 38 being carried thereon, said bolt being secured at its opposite end 36 to an extension member 39 mounted on the under side 28 of said string carrier. As the wing nut is revolved the string carrier moves toward that end of the base member, 40 thereby tightening said strings.

The strings 20 may be made from conventional gut or steel strings used on various musical instruments, depending upon the effect desired to be produced. We prefer to 45 employ a relatively heavy gut string, which is wound with suitable aluminum, silver or steel wire, in order to produce the desired base effect.

50 The following means are provided for pivotally mounting and actuating the damper.

An angle bracket 42 is secured by means of bolts 43 to an annular flange member 44 which is mounted within a conventional tympano as a support for the clamps 15.

The damper member is provided, on its under side, with two angle brackets 45 which secure said damper to a pair of diverging arms 45 which provide the 60 mounting for the damper. These arms are pivotally mounted at 47 to the end of the angle bracket 42. A link 48 is pivotally carried at the opposite end of the arms 45 by means of a bolt 49, said link being connected to a lower link 50 by means of an ad-

justing turnbuckle 51, the lower link having a ring portion 52 at its lower end.

The links are caused to move downwards, thereby raising the damper into engagement with the lower surface of the head 11 by 70 means of a foot pedal 53. The foot pedal may be of any conventional design. We prefer to employ a pedal having a base 54, a pedal member 55, hingedly connected to the base at 56, and a spring member 57 urging 75 said pedal upwardly. The pedal member 55 carries a finger 58 which engages the ring portion 52 of the lower link. A stop member 59 confines the upward swing of the pedal member. The pedal is preferably provided with a bracket 60 with an aperture 60' to provide means for connecting the pedal to one of the feet 61 of the stand 14, as by a bolt 62.

The hereinbefore described construction admits of considerable modification without departing from the invention; therefore, it is the wish not to be limited to the precise arrangements shown and described, which are as aforesaid, by way of illustration 80 merely. In other words the scope of protection contemplated is to be taken solely from the appended claims, interpreted as broadly as is consistent with the prior art.

We claim:

1. In combination with a percussion musical instrument having a head, a damper member mounted within said instrument and means for moving said damper member into engagement with the head of said instrument, said damper member including a supporting base, a plurality of strings in spaced relation thereto and means for mounting said strings on said supporting base, said means including, at one end of said base, a "U" shaped channel member and a piece of resilient material carried within said channel member forming a bridge for spacing said strings from said base, a block member at the end portion of said base for securing the ends of said strings, and, at the opposite end of said base, a sliding string carrier to which the opposite ends of said strings are secured, and means for adjustment of said string carrier longitudinally of the supporting base.

2. In combination with a drum and the like, a damper member and means for moving said damper member into engagement with the lower surface of the head of the drum, said damper member including a supporting base and a plurality of musical strings mounted taut on the upper surface thereof in spaced relation thereto, a lever pivotally mounted at its center within said drum, a link pivotally carried at one end of said lever, the damper member being rigidly mounted at the opposite end of said lever, and pedal operated means for drawing said link downwards, thereby bringing said damper 120 125 130

member into engagement with the lower surface of said drum head.

3. A device for attachment to a drum and the like including a damper member pivotally mounted within said drum and means for moving said damper into engagement with the lower surface of the head of said drum, said damper including a supporting base and a plurality of resonant strings mounted on the upper side of said base member in spaced relation thereto, and means for adjusting said strings, said damper moving means including a bracket member mounted within said drum, an arm pivotally mounted to said bracket, and foot pedal means for raising said damper member into engagement with the lower surface of the head of the drum.

4. A device for attachment to a percussion musical instrument having a head, and including a damper member pivotally mounted within said instrument and means for moving said damper into engagement with the lower surface of the head of said instrument, said damper including a supporting base and a plurality of resonant strings mounted in spaced relation thereto, said damper moving means including a bracket member mounted within said drum, an arm pivotally mounted at its center to said bracket, said damper member mounted at one end of said arm, and a link pivotally carried at the opposite end of said arm and a foot pedal connected with said link, whereby, when said foot pedal is depressed, the arm moves said damper member into engagement with the lower surface of the head of the drum.

5. A device for attachment to a drum and the like, including a damper member pivotally mounted within said drum and means for moving said damper into engagement with the lower surface of the head of said drum, said damper including a supporting base and a plurality of resonant strings mounted on the upper side of said base member in spaced relation thereto, and means for stretching said strings, said damper moving means including a bracket member mounted within said drum, an arm pivotally mounted at its center to said bracket, said damper member mounted at one end of said arm, and a link pivotally carried at the opposite end of said arm and a foot pedal connected with said link, whereby, when said foot pedal is depressed, the arm moves said damper member into engagement with the lower surface of the head of the drum.

Signed at New York city, in the county of New York and State of New York, this 6th day of June, A. D. 1931.

60 LORENZO SANSONE.
CESARE FRANCO.
